TUBING HEAD

Walter N. Thompson, La Habra, Calif.

Application March 5, 1934, Serial No. 714,034

7 Claims. (Cl. 166—14)

This invention relates to heads for wells and relates more particularly to tubing heads for oil and gas wells. It is a general object of the present invention to provide a simple, practical and effective well tubing head.

Tubing heads are provided on the upper ends of the casings of producing oil and gas wells to carry the tubing and to deliver the oil and gas to suitable lines or pipes connected therewith. The tubing heads that have been introduced have been constructed so that they must be disconnected and removed from the upper end of the well casing when it is desired to run tools into the wells or to remove the tubing. The removal of a tubing head from the well casing necessitates the disconnection of the pipes for carrying the oil and gas from the head and is usually a more or less difficult and prolonged operation.

It is an object of this invention to provide a tubing head that may remain on the well casing when tools are run into the well and when the oil tubing is removed from or run into the well. The tubing head provided by the present invention has an unobstructed opening as large or larger than that in the well casing and that is adapted to readily pass tubing catchers and other tools so that the head and the pipes connected therewith do not have to be disconnected from the well when tools are to be run into the well.

Another object of the invention is to provide a tubing head construction including a nipple member attached to the upper end of the well tubing having a flange or enlargement seated in the body of the head to support the string of tubing, said member having an enlarged head readily engageable by an elevator, thereby facilitating the lifting and handling of the tubing.

Another object of the invention is to provide a tubing head of the character mentioned in which the nipple member for supporting the string of tubing on the body of the head effectively divides or separates the interior of the body into upper and lower chambers or portions whereby the gas from the casing may directly discharge from a pipe communicating with the lower internal portion of the head and the liquid or oil from the tubing may directly discharge through a pipe communicating with the upper interior portion of the body.

It is another object of the invention to provide a tubing head of the character mentioned in which the upper portion of the body is threaded to receive a cap for carrying a stuffing box,

which cap is removable to render the lifting nipple accessible for engagement by an elevator and to permit an improved split spider to be threaded into the body for temporarily or optionally supporting the string of tubing when the tubing is 5 to be pulled from the well or run into the well.

A further object of the invention is to provide a tubing head that is easy and convenient to install and use and that is simple and inexpensive of manufacture.

Other objects and features of the invention will be best and fully understood from the following detailed description of typical forms and applications of the invention, throughout which description reference will be had to the accompanying drawings, in which:

Fig. 1 is a vertical detailed sectional view of one form of tubing head provided by the present invention, showing it on the upper end of a well casing and carrying the nipple member for supporting the tubing and the cap and stuffing box for sealing about the polish rod. Fig. 2 is a fragmentary vertical sectional view of the head with the cap removed, illustrating the method of engaging the nipple by an elevator. Fig. 3 is a 20 vertical detailed sectional view of the head while carrying the spider and slips for supporting the tubing. Fig. 4 is a reduced transverse detailed sectional view taken as indicated by line 4—4 on Fig. 3. Fig. 5 is a vertical sectional view of 25 another form or application of the invention, and Fig. 6 is a transverse sectional view taken as indicated by line 6—6 on Fig. 5.

The tubing head provided by the invention includes, generally, a body 10 adapted to be attached to the upper end of a well casing C, a nipple member 11 adapted to be attached to the upper end of the tubing T to support the tubing on the body 10, and a spider 12 to be attached to the body 10, when the nipple member 11 is withdrawn from the body, to carry slips S for engaging and supporting the tubing T.

The body 10 is an elongate tubular member to be attached to the upper end of the well casing C. The central longitudinal opening 13 of the 45 body 10 is in vertical and longitudinal alignment with the opening of the casing C and its lower portion 14 is screw threaded to receive the threaded upper end of the casing. An annular upwardly facing shoulder or seat 15 is provided 50 on the wall of the body opening 13 and is spaced between the opposite ends of the body. The seat 15 is preferably inclined downwardly and inwardly as illustrated throughout the drawings. Due to the provision of the shoulder 15, the up- 55

per portion of the body opening 13 is of enlarged diameter. It is a feature of the invention that the body 10 has an unobstructed opening 13 as large as or larger than the opening in the well casing C. The upper end portion 16 of the body opening may be threaded to receive the cap 17 and the spider 12.

The cap 17 is removably connected with the body 10. In the particular form of the invention illustrated in the drawings, the cap 17 is threaded into the upper portion 16 of the body opening. The cap 17 may be comparatively long and its upper end portion may be reduced to carry the stuffing box 18 for sealing about the polish rod P of the string of sucker rod, or pump rod R. The cap 17 and stuffing box 18 normally close off the upper end of the body 10 and the cap 17 is adapted to be removed or disconnected from the body when the tubing is to be removed from the well or when tools are to be run into the well casing C. In accordance with the invention, outlet openings are provided in the walls of the body 10. The opening 19 for the passage or discharge of gas from the casing C communicates with the body opening 13 at a point below the seat 15 and is adapted to receive the end of a suitable line or pipe 20. The opening 21 for the discharge of the liquid or oil from the body 10 communicates with the interior of the body at a point spaced 30 above the seat 15 and is adapted to receive the end of a conduit 22.

The nipple member 11 is adapted to be attached to the upper end of the tubing T and normally supports the string of tubing on the shoulder or seat 15 of the body 10. The nipple member 11 is an elongate tubular part having a central longitudinal opening 23 extending through it from one end to the other. The lower end portion of the opening 23 is threaded to receive or connect with the threaded upper end of the tubing T. The member 11 extends centrally through the opening 13 of the body and is sufficiently long to project a substantial distance into the cap 17. In accordance with the invention, the nipple member 11 is provided with a supporting and sealing flange or enlargement 24 adapted to cooperate with the seat 15 of the body. The flange or enlargement 24 is continuous or annular and is comparatively heavy. In accordance with the preferred construction, the enlargement 24 of the nipple member is spaced some distance above the lower end of the member and has an inclined lower end 25 operable to evenly engage or rest on the seat 15. The flange or enlargement 24 is proportioned so as to be readily passed into the upper portion of the body opening 13 with suitable clearance. Packing means is provided on the enlargement 24 to seal with the seat 15. A ring 26 of packing is carried in an annular groove in the lower face 25 of the enlargement to seal with the seat 15.

The weight of the string of tubing T holds the enlargement 24 in tight sealing engagement with the body seat 15. It is to be noted that the flange or enlargement 24 of the nipple member effectively separates and packs off the two opposite end portions of the body opening 13 and dependably supports the string of tubing T on the body shoulder 15. A head 30 is provided on the upper end of the nipple member 11 and its lower end is adapted to be engaged by a suitable elevator E, or the like. The head 30 is spaced a considerable distance above the upper end of the body 10. When the cap 17 is disconnected from the body 10, the head 30 is readily engageable by

the elevator E in the manner clearly illustrated in Fig. 2 of the drawings to facilitate the quick easy lifting of the tubing T. During pumping of the well or flowing of the well, the oil flows upwardly through the tubing T and discharges from the upper end of the nipple member 11 into the cap 17 and is carried off by the pipe 22, communicating with the upper end portion of the body opening. The gas flowing upwardly through the casing C is carried off by the pipe 20 connecting with the lower end portion of the body opening 13 below the enlargement 24 of the nipple member. 5 10

The spider 12 is adapted to be employed on the body 10 while pulling the tubing T from the well or while lowering tubing into the well. The spider 12 is operable to carry slips S for gripping and supporting the tubing. In accordance with the invention the spider 12 is adapted to be attached to the upper end of the body 10 when the cap 17 is removed from the body and the tubing T has been raised a sufficient distance to lift the nipple member 11 clear of the body. It is a feature of the present invention that the spider 12 is a split tubular structure adapted to be assembled around 25 the tubing T for ready connection with the body 10. The spider 12 includes two complementary semi-circular sections 31. The lower portions 32 of the sections 31 are threaded so that the spider may be threaded into the upper portion 16 of the body opening when the sections 31 are assembled or connected in proper registration. Dowels or pins 33 project from one section 31 and are adapted to be received in sockets in the other section to hold the sections against relative 35 longitudinal movement when assembled around the tubing and while being threaded into the body opening. Openings or sockets 34 may be provided in the sections 31 of the spider to receive suitable turning tools. 40

The central longitudinal opening 35 in the sectional spider 12 is operable to pass the tubing T with suitable clearance, and its upper portion 36 is in the nature of a downwardly and inwardly inclined seat to carry the slips S. The slips S 45 are adapted to be removably positioned on the seat 36 so as to dependably grip and support the tubing T. The inner sides of the slips S are provided with serrations or teeth 40 for gripping the tubing T. The outer sides of the slips S are 50 rounded and are inclined downwardly and inwardly to effectively cooperate with the seat 36.

It is believed that the utility and practicability of the tubing head provided by the present invention will be readily understood from the foregoing 55 detailed description. When the well is flowing or is being pumped, the cap 17 and stuffing box 18 close the upper end of the tubing head body 10 and the enlargement 24 of the nipple member cooperates with the body seat 15 to dependably 60 suspend or support the string of tubing on the body and to divide or separate the upper and lower portions of the body opening 13. The stuffing box 18 seals and packs about the reciprocating polish rod P of the string of pump rod R. The 65 upwardly flowing oil passes through the nipple member 11 and discharges from its upper end into the cap 17 to flow out of the pipe 22. The gas from the well casing C discharges through the pipe 20 which is in communication with the 70 body opening 13 at a point below the seat 15.

In the event that it is desired to run tools into the well or to pull the tubing T from the well, the cap 17 is disconnected from the body 10 to render the upper end portion of the nipple mem- 75

ber 11 accessible. After disconnection of the cap 17 from the body the head 30 of the nipple member may be engaged by the elevator E for the lifting or raising of the nipple member and string 5 of tubing connected therewith. As the nipple member 11 is not connected with the body 10 but merely has its enlargement 24 resting on the seat 15, it may be easily and quickly pulled out of the body without any other manipulation. After 10 removal of the nipple member 11 from the body 10 the spider 12 may be assembled around the projecting upper portion of the tubing T and threaded into the upper end 16 of the body. The slips S may then be arranged in the spider 12 to support the tubing T during the disconnection of the tubing as it is pulled from the well. The spider 12 and slips S also are adapted to support the string of tubing when it is again lowered into the well. It is to be particularly noted that the 15 body 10 of the tubing head provided by the present invention does not have to be detached from the well casing C when tools are to be run into the well or when the tubing is to be pulled from the well. The opening 13 of the body is larger than the opening in the casing C and is unobstructed 20 after the removal of the nipple member 11 to provide for the easy passage of tools, etc., into the well. The cap 17 is easily detached from the body 10 to permit the lifting engagement of the elevator E with the head 30 of the nipple member 11. The spider 12 may be easily and quickly assembled around the tubing and connected with the body 10 and may be readily removed when it is desired to again position the nipple member 25 11 on the seat 15. The tubing head of the present invention is simple and inexpensive of manufacture, and permits the operation of tools into the well and the removal of the tubing from the well without the necessity of disconnecting the body 30 of the head or the pipes connected therewith.

The application or embodiment of the invention illustrated in Figs. 5 and 6 of the drawings includes means for positively holding the string of tubing T against upward movement. A tubular member or sub 50 is interposed between the nipple member 11 and the reduced neck of the cap 17. The sub 50 is adapted to be threaded into the reduced upper end or neck of the cap 17. The lower end of the sub 50 is adapted to engage and bear downwardly against the upper end of the nipple member 11. The engaging or cooperating faces of the sub 50 and nipple member 11 may be beveled as at 51. In accordance with the invention the sub 50 passes the polish rod P with substantial clearance. The portion of the sub 50 within the cap 17 is perforated or provided with a multiplicity of openings 52 to permit the fluid pumped or flowing upwardly through the tubing T to freely discharge into the body 10. The portion of the sub 50 projecting upwardly from the cap 17 may be enlarged and provided with a threaded socket 53 for the reception of the threaded lower end of the stuffing box 18.

In some cases it may be desirable or necessary 65 to positively hold the string of tubing T against upward movement, for example, where high gas pressures exist in a well it may be necessary to prevent the string of tubing T from being blown from the well. When the string of tubing T is to be held down the sub 50 is threaded downwardly into the neck of the cap 17 so that its lower end engages the upper end of the sub to hold the flange enlargement 24 in tight cooperation with the shoulder 15. It will be apparent 70 how the sub effectively holds the string of tub-

ing T against upward movement and retains the enlargement 24 in engagement with the shoulder 15. The stuffing box 18 may be threaded into the upper end of the sub 50 to seal about the polish rod P in the usual manner. 5

Having described only typical forms and applications of my invention, I do not wish to be restricted or limited to the specific forms and applications herein set forth, but wish to reserve to myself any modifications or variations that 10 may appear to those skilled in the art or fall within the scope of the following claims.

Having described my invention, I claim:

1. A tubing head, including a body to be attached to a well casing and having a vertical 15 opening communicating with the casing, an upwardly facing seat on the wall of the opening, a removable cap on the upper end of the body, a tubular member adapted to be attached to the upper end of a string of tubing in the well, a part 20 on the member cooperating with the seat to support the string of tubing, the member projecting from the body into the cap, and a head on the member within the cap shaped for external engagement by an elevator when the cap is removed. 25

2. A tubing head, including a body to be attached to a well casing and having a vertical opening communicating with the casing, an upwardly facing seat on the wall of the opening, 30 there being a port in the wall of the body for the discharge of gas communicating with said opening below the seat and a port in the body wall for the discharge of liquid communicating with the said opening above the seat, a tubular member 35 adapted to be connected to the upper end of a string of tubing in the well to conduct liquid upwardly therefrom, a shoulder on the member removably seated on the seat to suspend the said string and to separate the portions of said opening 40 above and below the seat, and a tubular element threadedly connected with the body and cooperating with the member to hold the shoulder on the seat and communicating with the member, the element being adapted to receive a pump rod and 45 having a lateral port in its wall for discharging liquid into said opening above the seat.

3. A tubing head for use on the upper end of a well casing, including a body having a vertical opening as large in diameter as the opening of 50 the casing, an upwardly facing seat on the wall of the opening, a nipple to be attached to a string of tubing in the well, an annular enlargement on the nipple adapted to cooperate with the seat to support the tubing, the nipple projecting above 55 the body, a head on the projecting portion of the nipple engageable by an elevator, and a cap closing the upper end of the body and housing the projecting portion of the nipple, said cap being removable from the body to render the head accessible. 60

4. A tubing head for use on the upper end of a well casing, including a body having a vertical opening as large in diameter as the opening of 65 the casing, an upwardly facing seat on the wall of the opening, a nipple to be attached to a string of tubing in the well, an annular shoulder on the nipple adapted to cooperate with the seat to support the tubing and to seal the upper portion of the opening from the lower portion of the 70 opening, there being ports in the body communicating with said upper and lower portions of the opening for the discharge of liquid and gas respectively, a cap closing the upper end of the body and removable to render the nipple accessible. 75

ble for removal, and a part threaded into the cap to hold the nipple against upward movement.

5. A tubing head for use on the upper end of a well casing, including a body having a vertical opening as large in diameter as the opening of the casing, an upwardly facing seat on the wall of the opening, a nipple to be attached to a string of tubing in the well, an annular shoulder on the nipple adapted to cooperate with the seat 10 to support the tubing and to seal the upper portion of the opening from the lower portion of the opening, there being ports in the body communicating with said upper and lower portions of the opening for the discharge of liquid and gas 15 respectively, a cap closing the upper end of the body and removable to render the nipple accessible for removal, a threaded part for holding the shoulder on the seat, and a stuffing box carried by the cap for sealing about a pump rod operating 20 through the tubing.

6. A tubing head for use on the upper end of a well casing, including a body having a vertical opening as large in diameter as the opening of the casing, an upwardly facing seat on the wall

of the opening, a nipple to be attached to a string of tubing in the well, an annular enlargement on the nipple adapted to cooperate with the seat to support the tubing, the nipple projecting above the body, a head on the projecting portion of the nipple formed for external engagement by an elevator, and a cap closing the upper end of the body and enclosing the projecting portion of the nipple and its head, the cap being removable to render the nipple accessible for removal.

7. A tubing head including, a body to be attached to a well casing and having an opening communicating with the casing, an upwardly facing seat in the body opening, a member to be attached to the tubing and having a projecting part to rest on the seat to support the tubing and to separate the opposite end portions of the opening, a removable cap on the upper end of the body and means holding the tubing against upward movement, said means including an element 15 threaded into the cap and bearing downwardly against said member.

WALTER N. THOMPSON.
